UNITED STATES PATENT OFFICE

2,351,170

ABRASIVE DEVICE FOR CLEANING STILL
TUBES AND THE LIKE

Hermon G. Weinland, Springfield, Ohio, assignor
to Norton Company, Worcester, Mass., a corpora-
tion of Massachusetts

Application October 18, 1941, Serial No. 415,562

5 Claims. (Cl. 15—104.09)

The invention relates to a tube cleaner de-
signed for removing encrustations from the inter-
ior of tubes of boilers, stills, or the like.

One object of the invention is to provide a
tube cleaner capable of efficiently removing hard
and thick deposits of carbon or other encrusta-
tions. Another object of the invention is to pro-
vide an abrasive tube cleaner capable of remov-
ing catalyst balls and embedded carbon from a
still tube. Another object of the invention is to
provide a combination cutter and abrasive head
for cleaning still tubes to meet the most exact-
ing requirements. Another object of the inven-
tion is to save time in the cleaning of still tubes
for gasoline cracking whereby the periods of
shutdown will be shorter. Other objects will be
in part obvious or in part pointed out herein-
after.

The invention accordingly consists in the fea-
tures of construction, combinations of elements,
and arrangements of parts, all as will be illustra-
tively described herein, and the scope of the ap-
plication of which will be indicated in the fol-
lowing claims.

In the accompanying drawing illustrating one
of many possible embodiments of the mechanical
features of this invention,

Figure 1 is an axial sectional view of a still
tube, showing the tube cleaner of the invention
located therein illustrated in elevation;

Figure 2 is an axial sectional view of the tube
cleaner head, showing the parts on an enlarged
scale;

Figure 3 is an end view of the head on the
same scale as Figure 2;

Figure 4 is a cross sectional view, taken on the
line 4—4 of Figure 2, illustrating a locking de-
vice;

Figure 5 is a cross sectional view, on a reduced
scale, taken on the line 5—5 of Figure 2.

As conducive to a clearer understanding of the
present invention, it is noted that in the oper-
ation of stills for cracking petroleum and for
fractionating the higher hydrocarbons, the steel
tubes become encrusted with a carbonaceous de-
posit which is often very hard. My prior appli-
cations Serial No. 321,951 filed March 2, 1940,
and Serial Nos. 388,859 and 388,860 filed April
16, 1941, disclose abrasive tube cleaners which
have been found to be quite effective in prac-
tical operation. The still tubes are not all of
the same size, the conditions of operation vary
widely among different plants and in different
parts of the same plant, and the encrustations
consequently have different degrees of hardness

and sometimes fill the tube and at other times
constitute a layer upon the wall of the tube. In
certain operations still tubes are filled solidly with
a catalyst in the form of hundreds or thou-
sands of little balls. The material of the cat-
alyzer is corrosive when exposed to air. Oil is
pumped through the tubes between the balls and
after a period of operation, the interstices be-
tween the balls become solidly filled with coke.
The combination of balls bonded with coke is
extremely hard to remove. The apparatus of
the present invention is more particularly de-
signed to remove such difficultly removable de-
posits which solidly or practically solidly fill still
tubes.

Referring now to the drawing and first to Fig-
ure 1, a still tube to be cleaned of encrustation
is indicated at 10, the catalyst balls being in-
dicated at 11, and the coke or carbon between
the balls being indicated at 11a. The tool of
my invention may be mounted on the end of a
suitable air turbine 12 which is energized by
compressed air passing through a rubber hose
13 which is also used as a handle to push the
tube as above set forth. Such air turbines 12
mounted on the end of hoses 13 are now readily
available and will not, therefore, be particularly
described, and any other prime or secondary
mover may be provided within the scope of the
present invention. Such air turbines are capable
of revolving a cleaning tool at speeds of the
order of 1000 to 3500 R. P. M.

Still referring to Figure 1, at the end of the
turbine opposite the hose 13 is the driven spin-
dle 14. This, as is customary, is drilled and
tapped and fitted to a threaded clevis stud 15
which is connected to another threaded clevis
stud 16 by means of a link 17, these three parts
constituting a universal joint.

Referring now to Figure 1, I provide a nut 20
having a threaded bore 21 of small diameter
and a threaded bore 22 of larger diameter. The
threaded clevis stud 16 fits in the bore 21. Re-
ferring also to Figure 2, a spindle 23 has an en-
larged threaded end 24 which fits in the threaded
bore 22. The main body part of the spindle 23
is a rectangular parallelepiped which is rectan-
gular in cross section. Preferably also it has a
large diameter base 26 which is a thrust taking
part.

Onto the spindle 23 and around the base 26
is molded a cylindrical abrasive body 30. For
the manufacture of the body 30 I may proceed
as follows: Taking a quantity of silicon carbide
abrasive in coarse grit size, for example 10 to 16

mesh grit size, and placing it in a mixing pan, I add furfural and mix until each granule is coated with furfural. I mix together a quantity of "A" stage phenol formaldehyde, abrasive fines and quick lime. I add this mixture to the mixing pan while continuing the mixing. I then add a quantity of neutral creosote oil and continue the mixing until the creosote oil has been thoroughly distributed throughout the mass of ingredients in the pan.

The "A" stage phenol formaldehyde is preferably permanently fusible solid phenol formaldehyde resin with sufficient hexamethylene tetramine to harden it. The abrasive fines may be very fine particles of any suitable abrasive, for example, silicon carbide or aluminum oxide in grit sizes of the order of 400 to 600 mesh grit sizes. As a specific example of proportions for a suitable stick, I may make up an abrasive structure as follows:

	Per cent by volume
Abrasive	58
Bond	34
Pores	8

In the foregoing the "bond" comprises "A" stage solid resin 50% by weight, alumina fines 40% by weight, and quick lime, CaO, 10% by weight. I may use 65 cubic centimeters of furfural and 25 cubic centimeters of quick lime per pound of the above "bond."

The foregoing is given as an illustrative example only, but it is noted that there is thereby formed a hard abrasive structure of slight porosity. By reason of the incorporation of the abrasive fines in the bond, the bond itself is quite tough.

So far as the particular bonding ingredients are concerned and the proportions thereof, I may vary the foregoing widely and, in fact, other bonds besides phenol formaldehyde may be used, such as rubber, shellac and the like. But I have found that of the common abrasives now known, only silicon carbide is satisfactory and I also find that the abrasive structure should be hard and dense.

Referring now to Figure 5, I embed wires 31 in the abrasive body 30. These may be equilateral triangles, as shown in Figure 5. Preferably they are oriented so that the points of alternate wires are angularly spaced by 60 degrees. That is to say, a given bisection of one angle of one triangle will make an angle of 60 degrees with the nearest bisection of the angle of the nearest axially displaced triangle.

I have found that the combination of the use of silicon carbide and the embedded wires 31 gives an abrasive which will cut the encrustation 11 without detrimentally cutting the tube 10. The exact reason for this I do not know, especially since theoretically the wires 31 should wear away faster than the abrasive and also silicon carbide should abrade the steel of the tube. Nevertheless the results have been observed in actual practice and confirmed by repeated tests.

The cylindrical shape of the abrasive body 30 is modified by a frusto-conical head 33. This permits the tool to start cutting its way into the encrustation of carbon 11.

The spindle 23 has a threaded end 35 which is screwed into a cutting head 36. A washer 37 may be interposed between the cutting head 36 and the abrasive body 30. The cutting head 36 is preferably a piece of steel of generally cylindrical shape having a transverse rectangular

hole 38 symmetrically located therein and also having one end thereof cut away on the bias to receive a pair of cutters 40 and 41 mounted on a pin 42 which extends between sides 43 and 44 of the head 36 and is inclined to a plane perpendicular to the axis of the cylindrical member 36. This inclination is of the order of twelve degrees whereby the pin is inclined at of the order of 78 degrees to the axis of the cylindrical member 36 which is the axis of rotation of the entire tool. The axis of the pin 42 intersects the axis of the head 36. The pin 42 has a groove 45 therein into which fits a long pin 46 extending parallel to the axis of the head 36 and locked in position as shown; thereby the pin 42 cannot come out until the head 36 is unscrewed from the spindle 23.

The proper securing of the head 36 onto the spindle 23 is or may be somewhat of a problem. Referring now to Figure 4, in the lower part of the head 36 are recesses 50 and 51. A block 52, preferably made of brass or copper, is located in one recess and the head of a screw 53 is located in the other recess. The screw 53 extends through a partition 54 between recesses 50 and 51 and into a threaded hole in the block 52. By tightening the screw 53, the block 52 can be drawn against the threads of the threaded end 35 (the recess 50 extends to the threaded hole in the head 36 for the threaded end 35 of the spindle 23) and this action tends to lock the head 36 onto the spindle 23. The block 52 being made of brass or copper, will not spoil the threads on the end 35 but will apply friction thereto. Other soft metals can be used or other locking means employed.

Considering now the operation of the device, the air turbine 12 is introduced into the tube 10 by means of the hose 13 in the usual way and the air is turned on. The cutters 40 and 41 resemble gears, only the teeth are sharp instead of having any one of the conventional gear teeth shapes. Rapid rotation of these cutting wheels set on a bias cuts away the central part of the coke, catalytic balls or other obstructing matter. The action of the cutters 40 and 41 extends to a radial distance where the abrasive body 30 starts its action. The remainder of the radial distance to nearly the full radius of the still tube is cleaned by the abrasive body 30. Owing to the universal joint mounting and because of lack of any accurate bearing for the turbine 12, some play is allowed and the abrasive body 30 will actually clean the tube right to the metal. However, practical experience shows that such an abrasive body does not tend to injure the still tube 10 or cut away the steel thereof to any great extent. I prefer to use two cutters 40 and 41 because differential action is thereby obtained and each cutter revolves at approximately its most effective cutting speed.

The tool of the invention combines a pair of steel cutters with an abrasive cutter, the latter operating at a greater radial distance from the center than the former. The combination has proven effective to dig out the hardest encrustations, yet without damaging the still tube.

The effect of the wires 31 appears to be to create little metal islands as the abrasive wears away, which keeps the abrasive from wearing too fast. So far as I am aware the wires do not constitute reinforcing means, because experiments seem to show that the abrasive bodies 30 and 30a are actually stronger without such wires molded therein. The wires are too coarse to constitute proper reinforcing means. The action is, therefore, different and other than reinforcing, but at

all events superior results are obtained when using them.

The abrasive body 30 cuts a cylindrical path and this would still be true even if the body 30 were not a cylinder. Whatever the shape of the abrasive body 30, it will give a maximum cut defined by a circle the plane of which is normal to the axis of the spindle. The cutters 40 and 41 are at all times located within the projection of said circle, that is to say, any projection of said circle upon any plane normal to the axis of rotation of the whole unit. In that way the abrasive cutters 40 and 41 act as a pilot to cut out the center portion of the balls 11 and encrustation 11a while the abrasive 30 finishes the job and enlarges the hole.

It will thus be seen that there has been provided by this invention an article in which the various objects hereinabove set forth, together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In an apparatus for cutting encrustations on the interior wall of a tube of a still or the like, in combination, a spindle, a cylinder of bonded abrasive material molded onto said spindle and having a diameter approximating that of the tube whose encrustations are to be cut, the axis of the cylinder and the axis of the spindle substantially coinciding, a head at one end of the spindle, a pin mounted in said head having an axis intersecting the axis of the spindle but the axis of the pin being oblique to the axis of the spindle and the axis of the pin making an angle of less than forty-five degrees with a plane perpendicular to the axis of the spindle, and a cutting wheel mounted on said pin, the effective periphery of the cutting wheel having a diameter proportioned relative to the inclination of the pin axis so that, upon rotation of said spindle, the radius of the effective circular area of operation of the cutting wheel as the latter swings about the axis of said spindle is less than the radius of said cylinder of abrasive material, whereby the cutting wheel is kept out of cutting engagement with the wall of said tube and removes material in the center and the cylinder of bonded abrasive enlarges the hole as the whole apparatus rotates.

2. An apparatus for cutting encrustations on the interior wall of a tube of a still or the like comprising a rotary member having thereon an abrasive portion substantially concentric with said member and of substantially the inside diameter of a tube to be cleaned and tapering forwardly from a maximum to a minimum diameter, and other cutting means mounted on said member in advance of said abrasive portion, said other cutting means being adapted to clean a circular area the diameter of which corresponds substantially with the minimum diameter of said abrasive portion, said abrasive portion having a maximum diameter sufficiently greater than the diameter of the circular cutting area of said other cutting means to space said other cutting means from the 70 wall of the tube being cleaned, and having within itself at spaced intervals around its periphery,

metal islands positioned to that they are interposed between the main body of said abrasive portion and the wall of a tube into which said portion is inserted.

5. An apparatus for cutting encrustations on the interior wall of a tube of a still or the like, comprising a rotary spindle shouldered at one end and threaded at its other end, an abrasive element on said spindle and abutting at one end 10 against said shouldered end of the spindle, a head having mounted thereon cutter means which, with said abrasive element, upon rotation of the spindle operates upon encrustations and the like, said head having threaded means for 15 coating with the threaded end of said spindle to clamp said abrasive element against said shouldered spindle end and for holding said head assembled to said spindle, said abrasive element and said cutter means being of a relative size, and 20 relatively positioned so that said cutter means is spaced from the wall of the tube being cleaned by said abrasive element, and said abrasive element is operative in cutting the encrustation from the tube in an area surrounding and contiguous to the area in which said cutter is operative.

4. An apparatus for cutting encrustations on the interior wall of a tube of a still or the like, comprising a rotary spindle having thereon an abrasive element that has a generally cylindrical portion relatively long axially as compared to its radius and being of a radius to enter the tube, a head carried by said spindle adjacent the forward end of said abrasive element, said head carrying a metallic cutter means which upon rotation of said spindle has an effective cutting radius less than the radius of said abrasive element whereby said cutter means removes inner portions of the encrustations and is free from 35 direct contact with the wall of the tube, said abrasive element having exposed at its substantially cylindrical portion a plurality of metallic island-like surfaces substantially concentric with said cylindrical portion, said abrasive element operating to remove outer portions of the encrustation and having a maximum radius approximating the radius of the tube wall and said metallic island-like surfaces operating to lessen the possible abrading action of the abrading element on the metal of the tube.

5. An apparatus for cutting encrustations on the interior wall of a tube of a still or the like, comprising a rotatable mount having thereon an abrasive element presenting a substantially cylindrical operative surface of a radius approximating the radius of the tube and having thereon and in advance of said abrasive element rotatable cutter means with means rotatably supporting the latter from said mount to rotate about an axis making an angle with the axis of said mount, whereby, upon rotation of said mount, said abrasive element rotates therewith and said cutter means may rotate about said axis and partakes of rotary motion of translation about the axis of the mount, the maximum radius of the circular cutting area described thereby being less than the radius of said abrasive element, thereby to remove material from the tube at lesser radius than the latter and without contacting the wall of the tube.
